UNITED STATES PATENT OFFICE.

EMANUEL ROTHSCHILD, OF ANDERSON, INDIANA.

BOX.

1,069,649.

Specification of Letters Patent.

Patented Aug. 5, 1913.

Application filed November 22, 1911. Serial No. 861,698.

To all whom it may concern:

Be it known that I, EMANUEL ROTHSCHILD, a citizen of the United States, residing at Anderson, in the county of Madison 5 and State of Indiana, have invented new and useful Improvements in Boxes, of which the following is a specification.

The invention relates to boxes, more particularly to folded-blank boxes and has for 10 an object to provide a box made from a single piece of material and adapted to contain wearing apparel and the like.

In a large number of boxes now generally used, in department stores and the like, for 15 containing wearing apparel, the body of the box is fashioned from one piece of material, preferably cardboard and the cover for the body is fashioned from a second piece of material. In a box of this kind each of the 20 corners must be provided with locking lugs for securing portions of the box body and cover body to provide sides for the box body and overlapping portions for the cover body, thus necessitating a large amount of mate- 25 rial to properly construct the two parts of the box, namely the box body and the cover body. Furthermore, boxes of this nature are not substantially reinforced and the sides and ends of the box, as well as the bot- 30 tom of the box body and the top of the cover body tend to bulge outwardly and tear, any bulging of this kind being also adapted to disengage the locking members at each of the corners of the box.

35 In my device I employ a box portion and a cover portion, both made of an integral piece of material, preferably cardboard, the mentioned box portion and cover being pro- 40 vided with fewer locking members than the usual box described heretofore. By provid- 45 ing the cover portion to swing on the body portion and arranging straps to extend around parts of the body and cover por- tions, my box can be conveniently carried in the same manner that a suitcase or valise 50 is carried, portions of the strap being ar- ranged to constitute grips and the free end of the cover portion being adapted to lock with the free end of the box portion.

55 Reference is to be had to the accompa- 60 nying drawings constituting a part of this specification, in which similar characters of reference denote corresponding parts in all the views, and in which—

55 Figure 1 is a perspective view of a box, showing the same in closed position. Fig. 2

is a horizontal sectional view, looking down upon the bottom of the body portion of the box. Fig. 3 is a transverse sectional view taken on the line 3—3 in Fig. 1. Fig. 4 is an 60 enlarged fragmentary perspective view, showing the cover in partial open position and disclosing the manner of reinforcing the box portion and cover portion at the corners where the same are hingedly connected. Fig. 5 is a plan view of the blank 65 from which the box is folded.

Referring to the views and more particu- 70 larly to Fig. 5, I provide an integral piece of material 10, a portion 11 thereof constituting a box body and a portion 12 thereof constituting a cover body. The box body 11 is provided with ends 13 and a side 14, the ends 13 being formed of weakened portions 15 and the side 14 being formed by a weak- 75 ened portion 16. In a similar manner the cover body 12 is provided with ends 17 and a side 18, the ends 17 being formed by weakened portions 19 and the side 18 being formed by a weakened portion 20. The ends 80 13 of the box body 11 are provided with integral locking tongues 21 adapted to extend through slits 22 in the side 14 when the ends 13 have been bent laterally to the bottom 23 of the box body, the side 14 being also bent 85 laterally so that the locking tongues 21 can be inserted in the slits 22. Likewise the ends 17 of the cover body 12 are provided with locking tongues 24 adapted to extend through slits 25 in the side 18, the ends 17 90 being bent laterally to the top 26 of the cover body and the side 18 being also bent laterally to the top 26 so that the locking tongues 24 can be received in the slits 25.

95 Formed at the inner extremities of the 95 ends 13, and the ends 17 are reinforcing flanges 27, the said reinforcing flanges be- 100 ing formed by weakened portions 28 and adapted to be bent laterally inward from the ends 13 and 17 respectively and the in- 105 inner longitudinal extremity of the box body is provided with a weakened portion 29, the inner extremity of the cover body being pro- 110 vided with a weakened portion 30, so that when the box body and the cover body are bent on the weakened portions 29 and 30, the reinforcing flanges 27 of the box body 11 will overlap the reinforcing flanges 27 of the cover body 12 as shown more particu- 115 larly in Fig. 4, it being understood that the various locking members have been inserted in the slits formed in the sides 14 and 18

of the box body 11 and the cover body 12 respectively. Thus when the cover body 12 is swung on the weakened portion 30 to engage the cover body with the box body 11, 5 the laterally bent ends 17 and the laterally bent side 18 of the cover body will overlap the laterally bent ends 13 and the laterally bent side 14 of the box body 11 as shown in Figs. 1, 2 and 3, it being understood that 10 that portion of the piece of material 10, between the weakened portions 29 and 30 and which I will designate by the numeral 31, constitutes the inner side for the box body 11.

A strap 32 is passed inwardly through an 15 opening 33 in the top 26 of the cover body 12, the said strap being then passed outwardly through an opening 33^a and extended around the outer side of the portion 31, after which the strap passes inwardly 20 through an opening 33^b in the box body 11, the said strap being then passed outwardly through an opening 33^c in the box body to constitute a grip 34, the said strap being then passed inwardly through an opening 25 35 in the box body and then passed outwardly through an opening 35^a in the box body, the said strap being then passed around the outer side of the portion 31, after which the strap is passed inwardly 30 through an opening 35^b in the cover body 12, after which the strap passes outwardly through an opening 35^c in the cover body, and terminates in a grip 36, the grips 34 and 35 being of equal length and arranged so 35 that the person carrying the box can conveniently secure both grips with one hand. It will be seen that the strap 32, at the points where the same passes through the outer side of the portion 31, acts as a reinforcement for this part of the box and prevents the portion 31 from bulging when articles of apparel are placed within the box.

Formed on the side 14 of the box body 11 is a locking member 37, the said locking 40 member being adapted to extend through a slit 38 formed in the side 18 of the cover body 12, to lock the free end of the body 12 to the free end of the box body 11 as shown in Fig. 1.

From the foregoing description, it will be 50 seen that a box is provided in which the cover portion and the body portion are made of an integral piece of material, in which fewer interlocking joints are provided than 55 in the boxes now generally used and which consists of independent cover and body portions, in which the free end of the cover portion is adapted for locking engagement

with the free end of the body portion and in which a strap is provided, the said strap 60 constituting grips for enabling the user to easily carry the box with portions of the said strap constituting reinforcing means for the box.

I claim:—

1. A one-piece collapsible box of substantially rectangular form including a body portion, a cover portion, an intermediate portion connecting the said body and the cover portions and forming the rear wall of 70 the box, coextensive side and front walls formed on said body and cover portions and adapted to overlap when the box is in its closed position, and similarly constructed reinforcing members formed on the inner 75 ends of the side walls of the cover and body portions, said members adapted to overlap for engagement with the inner face of the connecting rear wall of the box.

2. A one-piece collapsible box of substantially rectangular form including a body portion, a cover portion, an intermediate portion connecting the said body and the cover portions and forming the rear wall of the box, coextensive side and front walls 85 formed on said body and cover portions and adapted to overlap when the box is in its closed position, and similarly constructed reinforcing members having beveled side 90 edges formed on the inner ends of the side walls of the cover and body portions, said members adapted to overlap for engagement with the inner face of the connecting rear wall of the box.

3. A one-piece collapsible box of substantially rectangular form including a body portion, a cover portion, an intermediate portion connecting the said body and the cover portions and forming the rear wall of the box, coextensive side and front walls 100 formed on said body and cover portions and adapted to overlap when the box is in its closed position, and similarly constructed reinforcing members formed on the inner 105 ends of the side walls of the cover and body portions, said members adapted to overlap for engagement with the inner face of the connecting rear wall of the box, said members being equal in length to approximately half the width of the rear wall.

In testimony whereof I affix my signature in presence of two witnesses.

EMANUEL ROTHSCHILD.
